CAST-IRON PIPE.

1,195,830.

Specification of Letters Patent. Patented Aug. 22, 1916.

Application filed May 18, 1915. Serial No. 28,968.

To all whom it may concern:

Be it known that I, JAMES R. MCWANE, a citizen of the United States, residing at Birmingham, in the county of Jefferson and State of Alabama, have invented a new and useful Cast-Iron Pipe, of which the following is a specification.

This invention has reference to cast iron pipe, and its object is to provide a form of pipe wherein certain objections to standard cast iron pipe are overcome.

Standard cast iron pipe is cast in upright molds in units of relatively great length with one end a spigot end and the other a bell end. Experience has shown that such pipes must be cast with walls of considerable thickness and oftentimes much thicker than is needed in service in order to overcome the possibility of the development of defects which would render the pipe units useless for the purpose for which they are intended.

There is considerably more metal in the standard cast iron pipe unit than is necessary for many purposes, but the excess metal has been put into the castings because of the difficulty in making a sound casting with less metal and because it has been found that a pipe made of lighter section is liable to break in handling.

On account of the difficulties in casting solid pipes in thin section even though the pressure to be withstood would warrant such thin section, there has been a very material waste in the employment of excess metal and in the payment of freight upon such excess metal.

There are many purposes where cast iron pipe of much lighter section than is customary could be used, provided such pipes could be molded successfully, and could be handled to the destination without breakage. The pressure in gas mains and in many water supply lines is a relatively very light pressure, and hence a light section would serve every purpose.

A cast iron pipe providing a pipe employing very materially less metal than heretofore, and yet having an inherent strength resisting breakage, and meeting the conditions present in the casting of the pipes in upright molds, is realized by the present invention. The improved pipe follows the lines of ordinary cast iron pipe in having a bell end and a spigot end, which may each be of a thickness throughout which experience has shown

to be necessary to avoid breakage. Between these ends and representing by far the greater portion of the length of the pipe, the full thickness is continued in the form of longitudinal ribs of considerable circumferential breadth, and these ribs are joined by circumferential ribs, or by spiral or helical ribs of relatively short pitch, whereby a very material portion of the surface of the pipe between the two ends is of reduced thickness between the longitudinal and circumferential ribs, so that the reduced portions are in the form of panels. Such a pipe is especially adapted for casting in upright molds and for casting in units of full length and integral throughout, and particularly does such a pipe avoid the troubles heretofore encountered in casting light one-piece pipes in upright molds.

The attempt has been made to produce sectional pipe, that is, pipe made of two or more pieces forming standard units of length, with the surface ribbed, but in such instances the construction has been such as to preclude the successful casting thereof in upright molds for, reasons which will hereinafter appear.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified, so long as such changes and modifications mark no material departure from the salient features of the invention.

In the drawings:—Figure 1 is an elevation of a pipe constructed in accordance with the invention with a portion of each end broken away to show the cross-sectional shape thereof. Fig. 2 is a transverse section of Fig. 1 through a set of panels, the showing of the figure being on a larger scale than Fig. 1. Fig. 3 is an elevation of a fragment of the pipe showing a modified arrangement.

Referring to the drawings, and especially to Figs. 1 and 2, there is shown a pipe 1 such as is employed in gas and water pipe lines, and such pipe has a spigot end 2 and a bell end 3 of standard form. Such pipes

are one-piece structures, and are made of cast metal. The mold employed is filled with the molten metal while the mold is in the upright position with the bell end downward. As these pipes have been heretofore molded experience has shown that both as a matter of strength and to permit the casting of the pipes, the thickness of the metal of the walls of the pipe must reach a certain amount. If the walls of the pipe be as thin as they might be for the service to which the pipe is put, then the dropping of the hot metal poured into such thin space as would represent a thin walled pipe, scatters as it drops and is cooled off to such an extent that when it finally settles such cooled off particles do not coalesce and the result is an imperfect casting and a leaky pipe. Moreover, a pipe as thin as the service would permit is liable to break at the spigot end during transportation. Should it happen that there are any impurities in the molten metal they are liable to lodge in a thin walled pipe and cause a leak. Because of such conditions it is the custom to cast the pipe with thick enough walls to sufficiently strengthen the spigot end, which is the end liable to be broken, and to prevent the formation of what is known as "cold shots" due to the scattering and cooling off of the metal when poured into a thin space from above, or the lodgment of impurities liable in thin walled pipes to produce leaks. To overcome all these difficulties of casting and at the same time materially reduce the weight of the pipe without sacrifice of any of the advantages, the pipe is formed with a circular series of longitudinal ribs 4 extending from the spigot end 2 where the pipe is of full thickness all the way around, to the bell end 3 where the pipe is also of full thickness all the way around. The ribs 4 are likewise of full thickness and are joined at suitable intervals by transverse circumferential ribs 5 which in Fig. 1 are shown as perpendicular to the ribs 4, but these ribs may be otherwise arranged with relation to the longitudinal ribs 4, as, for instance, there may be generally circumferential ribs 5^a extending spirally or helically about the pipe, as in Fig. 3.

In either instance the spaces bounded by the longitudinal and transverse ribs have the walls much thinner, these spaces being in the form of panels 6 of suitable shape. The interior of the pipe is smooth or unbroken throughout and of standard diameter, while the exterior of the pipe at the points corresponding to the spigot end 2, the bell end 3 and the ribs 4 and 5 or 5^a are all of a thickness of wall which experience has taught meets the conditions of casting and strength. The thickness of the walls of the panels 6, however, may be quite materially less than that of the ribs and other

like thick parts, since for many purposes such walls have to withstand but very little internal pressure.

For each panel there is a considerable saving of metal and the aggregate saving in a cast iron pipe is enough to represent a large saving in material and in cost of transportation, so that in the case of a single foundry the annual saving represents a matter of many thousands of dollars.

In casting a pipe such as represented in the drawings the pouring gates of the mold may coincide with the longitudinal ribs 4, which latter are represented in the mold by channels of ample width and depth.

In the pouring the hot metal quickly gravitates to the lower end and then the level of the accumulating metal rises with the hot metal rapidly finding its way through the transverse channels and into the thin walled panels. The relatively thick masses of metal accumulating in the channels represented in the spaces provided for the formation of the ribs 4 maintain the heat of the metal at such high point that there is no scattering or formation of "cold shots" during the pouring operation. Moreover, in the event of there being any impurities in the metal being poured, these impurities tend to accumulate in the channels corresponding to the ribs of the finished pipe, wherefore only pure metal finds its way into the thin walled parts representing the panels, so that these panels have their walls perfect and hence the metal is solid and well knitted together, and leaks are less likely to occur.

Those parts of the mold corresponding to the ribs form channels through which the hot metal is conducted in relatively thick masses and provide gates through which the molten iron is carried to the thin portions. The ribs not only contribute to the production of a sound casting despite the thin walls of the panels, but also provide ample strength for the casting and prevent breakage in handling.

When a cast iron pipe is broken in handling the break usually occurs at the spigot end which is the weak part. By carrying the ribs throughout the length of the pipe to about within six inches of the spigot end and forming such spigot end of the same section as in any ordinary bell and spigot cast iron pipe, such full or plain portion of full thickness serves to strengthen the pipe at the weak point, and it also furnishes a full, smooth surface for calking.

A cast iron pipe such as shown in the drawing has all the strength for many purposes of a cast iron pipe of full thickness throughout, and, moreover, is materially lighter in weight, this representing a corresponding material saving in metal and a very material saving in transportation costs.

The improved pipe besides being excel-

lently suited for purposes where there is internal pressure, is even better suited for use where the strain is external, as, for instance, in the case of culverts. Because of the saving in metal and transportation costs cast iron pipes constructed as herein described can economically be used in places of other types of metal culverts, because cast iron has lasting qualities when used underground 10 which is not found in metal culverts which have only the advantage over cast iron culverts in the matter of lightness and cheapness, which advantages are in a large measure present in the improved pipe of this 15 invention.

While it has been heretofore proposed to produce pipes of short lengths longitudinally divided into sections and provided with external ribs, the arrangement has been 20 such as to prevent the formation of such sectional pipes in vertical molds, nor could such ribbed sectional pipe be cast of such light weight as is provided by the pipe herein described with the great degree of strength 25 and the uniform distribution thereof.

What is claimed is:—

1. A one-piece cast iron pipe having end and body portions with the latter provided with external depressions forming panels 30 with walls of less thickness than the walls of standard pipe of the same internal diameter, said panels being arranged to define on the exterior of the body portion of the pipe longitudinal ribs and inter-connecting 35 lateral ribs, said ribs corresponding in thickness diametrically of the pipe to the thickness of the wall in standard cast iron pipe of the same internal dimensions, whereby the longitudinal rib-producing channels 40 in the mold provide passageways for relatively thick masses of molten metal during pouring and thereby prevent the formation of cold shots and at the same time segregate impurities, and whereby the weight of the 45 pipe is lessened over that of standard pipe of the same dimensions by the reduction in thickness of the walls of the pipe at the panel portions.

2. A one-piece cast iron pipe having end 50 portions joined by longitudinal relatively broad ribs with interconnecting relatively broad ribs joining the longitudinal ribs, said longitudinal and connecting ribs defining panels with the end portions of the 55 pipe and the ribs having a thickness corresponding to the thickness of wall of standard cast iron pipe of the same internal dimensions and the panel portions being of less thickness of wall than the ribs.

60 3. A one-piece cast iron pipe having spigot and bell portions of smooth exterior

with longitudinal ribs disposed about the body of the pipe and connecting the end portions, and laterally extended ribs connecting the longitudinal ribs, the lateral and 65 longitudinal ribs defining panels with the walls of the pipe at the ribs and at the spigot and bell portions of substantially equal thickness, and with the walls of the panel portions of less thickness than the 70 first-named portions.

4. An elongated one-piece cast iron pipe having a circular series of substantially parallel longitudinal ribs on its exterior of a thickness of wall permitting the casting of 75 the pipe in an upright mold and with thin walled portions between the ribs, whereby during the casting operation the channels in the molds in which the longitudinal ribs are formed provide passageways for relatively thick masses of molten metal segregating impurities and preventing the formation of cold shots, and also distributing the molten metal to the thin walled portions between the ribs. 80

5. A one-piece cast iron pipe having series of depressed portions on its exterior surface to there produce relatively thin pipe walls of less thickness than the thickness of wall of standard cast iron pipe of the same internal dimensions, those portions of the pipe walls between the depressed portions corresponding in thickness to the thickness of wall of standard cast iron pipe of the same internal dimensions and extending both 95 longitudinally and laterally of the pipe to admit of the formation in a vertical mold of a light weight pipe substantially free from material imperfections due to cold shots or impurities. 100

6. A one-piece cast iron pipe having on its exterior longitudinal ribs corresponding in diametric thickness to the thickness of wall of standard cast iron pipe of the same internal dimensions, said ribs being spaced 105 about the pipe in accordance with the spacing of and in alinement with the pouring gates of the mold in which the pipe is cast, whereby the channels in which the ribs are formed convey and distribute the metal to 110 the portions of the mold between the rib-forming channels and whereby the pipe is prevented from breakage in handling and under pressure.

In testimony, that I claim the foregoing 115 as my own, I have hereto affixed my signature in the presence of two witnesses.
